11 Claims. (Cl. 37—90)

This invention relates to and provides improvements in trenching machines.

The conventional trenching machine comprises a digger unit with an endless bucket line supported at the outer ends of two outward extending arms whose inner ends are pivotally attached to a vehicle. One arm is mounted above the other and a hydraulic piston and cylinder assembly is interposed therebetween for raising and lowering the trenching apparatus.

The digger unit of this conventional trenching machine is subject to abrupt and violent "pitching," with the moving of the vehicle over rough ground. This frequently results in broken parts and in a general shortening of the life of the machine. Another common fault is a ceaseless chattering of the arms.

We have discovered that the "pitching" of the digger unit may be greatly reduced by lowering the inner pivot point of the upper arm. But the lowering of this pivot point gives rise to new problems and necessitates the design and construction of a new combined supporting frame and lift assembly for the digger unit.

The inner pivot of the upper arm of the conventional trenching machine is necessarily placed relatively high to permit the raising of the digger unit above the ground. The lowering of this pivot point with the retention of the conventional arms and the hydraulic piston and cylinder disposed therebetween would result in a trenching machine comparatively restricted in the height to which its digger unit could be raised.

In our trenching machine, we have lowered the pivot point of the upper arm without unduly limiting the height to which the digger unit may be raised. Generally speaking, the invention contemplates in a trenching machine for attachment to a vehicle, the combination comprising an outwardly extending upper stabilizer arm pivotally supported at its inner end to the vehicle, and an outwardly extending lower stabilizer arm pivotally supported at its inner end to the vehicle at a point lower than the pivot of the upper stabilizer arm. Means is pivotally connected to the upper stabilizer arm and to the lower stabilizer arm at locations spaced from their pivoted ends for applying a spreading force between the two arms. An endless digger unit is disposed at the outer ends of the upper and lower stabilizer arms, the digger unit being pivotally connected to the upper stabilizer arm and slidably and pivotally coupled to the lower stabilizer arm so that relative movement between the digger unit and the lower stabilizer arm is permitted in a vertical direction.

In one form of the invention, the means for applying the force between the upper and lower stabilizer arms comprises a composite lower stabilizer arm which includes as one component an outwardly extending third arm pivotally supported at its inner end to the vehicle at the point lower than the pivot of the upper stabilizer arm and inward of the pivot of the other component of the lower stabilizer arm. The outer end of the third arm is coupled to the other lower stabilizer arm component

2

at a point spaced from the pivoted end of the lower stabilizer arm. The two ends of a hydraulic piston and cylinder assembly are respectively connected to the upper stabilizer arm and to the third arm component, so that the hydraulic assembly and the third arm can be operated to apply force between the upper and lower stabilizer arms.

A frequent shortcoming of many trenching machines is the tendency to spill dirt back into the trench being dug. We have overcome this shortcoming by providing in a trenching machine of the type having an endless bucket line, the combination comprising a wheel having an open center and an earth conveyor extending transversely through this wheel. The bucket line rides over the wheel, dumping earth from the several buckets onto the transverse conveyor. We have found that a relatively large wheel is preferred because the dumping is smoother and more gradual than with a smaller wheel. Preferably, the bucket line is carried at its opposite end by a second wheel spaced beneath the open center wheel. In our preferred embodiment, the two wheels are sprocket gears and the lower gear is smaller than the upper.

These and other aspects of the trenching machine of our invention will be more clearly understood in the light of the following detailed description taken in conjunction with the accompanying drawings, wherein:

Fig. 1 is a side elevation of the trenching machine of the invention, showing the machine attached to a tractor with one track of the tractor removed;

Fig. 2 is a longitudinal section of the trenching machine of Fig. 1, taken along line 2—2 of that figure; and

Fig. 3 is a cross section through an upper drive sprocket of the trenching machine of Fig. 1.

The trenching apparatus shown in the drawing is attached to a tractor 10, and comprises two major assemblies, a digger unit 11 and a combined supporting frame and lift assembly 12, and a transmission 14 coupled to the engine of the tractor.

The supporting frame and lift assembly is made up of three pairs of rearwardly extending arms 25, 26, 40 which are pivotally connected at their forward ends to the tractor, two hydraulic piston and cylinder assemblies 16, a slip clutch assembly 17, and requisite power transmission gears and chains. The transmission 14 through a chain 18 drives a gear 19 affixed to one end of a shaft 21 which is journaled in an upright pedestal 23 bolted to the top of the tractor frame. The other end of the shaft 21 carries the slip clutch assembly which in turn transmits power to a head shaft 22 of the digger unit through a drive chain 24.

Two of the pairs 25, 26 of rearwardly extending arms, couple and stabilize the digger unit to the tractor, with the arms of each pair being spaced from each other a distance sufficient to give operating clearance for the bucket line 27 which lies therebetween. Two relatively short upright and spaced brackets 29 (see Fig. 2) are affixed to the upper surface of a horizontally and transversely disposed channel beam 30 of the digger frame and are pivotally connected to the head shaft 22. The head shaft is journaled in the trailing ends of the two upper arms 25. In other words, the digger unit is suspended from the head shaft. The upper arms 25 are pivotally supported at their forward ends on the shaft 21 which carries the slip clutch assembly 17.

The lower pair of stabilizer arms 26, which are considerably shorter than the upper pair, are hinged at their trailing ends to the digger unit by a shaft 32 of a slide assembly 33 which is slidably mounted on an upright beam 35 of the digger unit frame. A shaft 37 is journaled in a flange member 38 depending from the tractor chassis and pivotally supports the forward ends of the lower

stabilizer arms on an axis below and rearward of the forward pivot of the upper stabilizer arms.

A third pair of arms 40 are pivotally mounted at their forward ends on a shaft 42 journaled in a support 43 directly beneath the pivot of the upper pair and below the pivot of the lower pair of stabilizer arms. The rearward and upwardly bent ends of the third pair are respectively pivotally connected to the undersides of the two lower stabilizer arms by two relatively short links 45 at corresponding points intermediate the forward ends and midpoints of the two stabilizer arms.

The two hydraulic piston and cylinder assemblies are respectively pivotally connected between the arms of the upper stabilizer pair and the arms of the third pair. The piston shaft of each assembly is pivotally connected adjacent the midpoint of the respective upper stabilizer arm near the pivot end of the respective arm and the cylinder of each assembly is pivotally connected adjacent the forward end of the respective third arm.

The digger unit illustrated has an endless bucket line which is carried at its respective ends over two relatively large, upper, coaxially spaced drive sprockets 49 and two smaller, coaxially spaced, lower idler sprockets 50. We have found that by employing upper sprockets which are relatively large, the dumping of the several buckets as they pass over the upper sprockets is smooth and gradual and free of the "quick snap" common to other trenching machines. A "quick snap" dumping of a bucket throws dirt on the bucket ahead and frequently spills into the trench being dug. The lower idler sprockets, instead of having the conventional ring of circumferential teeth, have spaced sets of three teeth. These sets of teeth are spaced at intervals around the circumference of each lower sprocket at proper distances to mesh with the several links 61 of the bucket line.

The frame of the digger includes two downwardly converging elongated beams 35, 51 which are spaced apart near their upper ends by a cross beam 52. The lower ends of the two elongated beams are held together by two plates 54 (Fig. 2) fastened between respective sides of the two beams. A shaft 56 journaled in the two plates supports at its opposite ends the two idler sprockets 50.

The beam 35 supports at its upper end the transverse channel beam 30, previously described. Two triangular-shaped gusset plates 57 (Fig. 2) are welded to opposite sides of this beam and to the underside of the overlying channel beam 30. A beam 58 of the same length as the horizontal and transversely disposed channel beam 30 lies parallel to and in the same horizontal plane as such beam and is affixed to the upper end of the beam 51 of the digger frame.

Each of the upper drive sprockets has an outer ring 60 of outwardly projecting teeth which mesh with the several links 61 of the bucket line and also a ring of internal teeth 63. Each sprocket (seen best in the cross section of Fig. 3) also has an internal circumferential inwardly projecting flange 64, spaced from the internal teeth.

Each of the two drive sprockets is supported by three idler rollers 66, 67, 68 and is driven by a separate pinion gear 69. Identically functioning parts associated with the two sprockets are identified by the same numbers. The corresponding rollers of the two sprocket assemblies are mounted on common shafts. The two pinion gears and the two rollers 66 are affixed to the head shaft 22 (Fig. 2) which hinges the digger unit to the upper pair of stabilizer arms. A shaft 70 journaled in two spaced brackets 71 fastened to the top of the horizontal beam 58 (inside of the circumference of the drive sprockets) carries the rollers 67 at its opposite ends, and a roller shaft 73 rotatably mounted on the top of the cross beam 52 mounts the rollers 68. The two pinion gears respectively mesh with the internal teeth of the two drive sprockets, with the several rollers rotatably engaging the inwardly projecting flanges 64 of the two sprockets.

Power is supplied to the digger unit from the transmission 14 coupled to the tractor through chain 18, shaft 21, slip clutch 17 and the drive chain 24 to the head shaft 22. The two pinion gears affixed to the head shaft mesh with the internal teeth of the two upper sprockets, driving these sprockets whose outer circumferential teeth engage and drive the bucket line.

The two parallel, horizontal and spaced beams 58, 30 support at their opposite ends a driving roller 75 and an idler roller 76 of an endless belt conveyor 77. The belt of the conveyor is horizontally disposed and extends transversely of the digger inside of the two drive sprockets, with the two ends of the conveyor spaced some distance from the sides of the digger. The conveyor is driven from a sprocket 78 mounted on an outer end of the head shaft through a two-way gear box 79 affixed to the digger frame and a chain or belt 80. By changing the direction of rotation of the gears of the two-way gear box, earth carried by the conveyor may be dumped on either side of the trenching machine.

An elongated, narrow guide plate 82 fastened to the bottom of the digger frame beam 35 runs the length of and is spaced from this beam by several cleats 83. The plate continues upward from the upper end of the beam 25 and is bent down and over the head shaft 22, forming a chute 85 for channeling the earth dumped from the buckets onto the conveyor belt. A second chute 87 (Fig. 1) is fastened to the opposite side of the digger frame for the same purpose. The guide plate lessens the "slapping" of the bucket line which rides thereon.

To raise the digger unit, fluid under pressure is introduced through a common line (not shown) to the two hydraulic cylinders through connections 89 from a pump and reservoir (neither shown), forcing the upper stabilizer arms 25 upward and the third pair of arms 40 downward. The lower stabilizer arms 26 are pulled downward by the third pair, and their trailing ends which are slidably held to the beam 35 continue in this direction until the slide assembly engages a stop 90 affixed to the beam. At this time the force exerted upward at the rear end of the upper stabilizer arms being greater than force acting downward at the stop causes the lower stabilizer arms and the third pair to move upward. Continued introduction of fluid under pressure to the cylinders raises the digger unit out of the trench. To lower the digger unit, hydraulic pressure is removed and the weight of the unit causes the digger to descend.

The trenching machine described employs three pairs of arms; however, the several features of the invention could be incorporated in a trenching machine having three single arms and a single hydraulic piston and cylinder assembly.

We claim:

1. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point lower than the pivot of the upper stabilizer arm and inward of the pivot of the lower stabilizer arm, the outer end of the third arm being coupled to the lower stabilizer arm at a point spaced from the pivoted end of the lower stabilizer arm, a hydraulic piston and cylinder assembly with its two ends respectively connected to the upper stabilizer arm and to the third arm, an endless digger unit disposed at the outer ends of the upper and lower stabilizer arms, means pivotally connecting the digger unit to the upper stabilizer arm and means slidably connecting the digger unit to the lower stabilizer arm.

2. In a trenching machine for attachment to a vehicle, the combination comprising an outwardly extending upper stabilizer arm pivotally supported at its inner end

75 per stabilizer arm pivotally supported at its inner end

to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point lower than the pivot of the upper stabilizer arm and inward of the pivot of the lower stabilizer arm, with the outer end of the third arm being coupled to the under side of the lower stabilizer arm at a point spaced from the pivoted end of the lower stabilizer arm, means connected to the upper stabilizer arm and to the third arm at locations spaced from their pivoted ends for applying a force between the two arms, an endless digger unit disposed at the outer ends of the upper and lower stabilizer arms, means pivotally connecting the digger unit to the upper stabilizer arm, and means slidably coupling the digger unit to the lower stabilizer arm so that relative movement between the digger unit and the lower stabilizer arm is permitted in a vertical direction.

3. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point lower than the pivot of the upper stabilizer arm and inward of the pivot of the lower stabilizer arm, the outer end of the third arm being coupled to the lower stabilizer arm at a point spaced from the pivoted end of the lower stabilizer arm, means connected to the upper stabilizer arm and the third arm at points intermediate their midpoints and pivoted ends for applying a force between them, an endless digger unit disposed at the outer ends of the upper and lower stabilizer arms, means suspending the digger unit from the upper stabilizer arm, and means slidably coupling the digger unit to the lower stabilizer arm.

4. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end directly beneath the pivot of the upper stabilizer arm, and inward of the pivot of the lower stabilizer arm, the outer end of the third arm being beneath and coupled to the lower stabilizer arm to a point intermediate of the lower stabilizer arm's pivoted end and middle, a hydraulic piston and cylinder assembly interposed between the upper stabilizer arm and the third arm, the piston and cylinder being respectively pivotally connected to the arms at points intermediate their midpoint and their pivoted ends, an endless digger unit disposed at the outer ends of the upper and lower stabilizer arms, and means coupling the digger unit to the ends of the upper and lower arms so that the spacing between the ends of the arms is adjustable.

5. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point lower than the pivot of the upper stabilizer arm and inward of the pivot of the lower stabilizer arm with the outer end of the third arm below the lower stabilizer arm, a short link hinged respectively at its opposite ends to the outer end of the third arm and to the lower stabilizer arm at a point spaced from its pivoted end, a hydraulic piston and cylinder assembly with its two ends respectively connected to the upper stabilizer arm and to the third arm, an endless dig-

ger unit disposed at the outer ends of the upper and lower stabilizer arms, means suspending the digger unit from the upper stabilizer arm and means coupling the digger unit to the lower stabilizer arm so that the spacing between the ends of the upper and lower stabilizers arms is adjustable.

6. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point lower than the pivot of the upper stabilizer arm and inwardly and lower than the pivot of the lower stabilizer arm, a short link hinged respectively at its opposite ends to the outer end of the third arm and to the lower stabilizer arm between its midpoint and pivoted end, a hydraulic piston and cylinder assembly pivotally connected respectively at its two ends to the upper stabilizer arm between its midpoint and pivoted end and to the third arm between its midpoint and pivoted end, an endless digger unit disposed at the outer ends of the upper and lower stabilizer arms, means pivotally connecting the digger unit to the upper stabilizer arm, and means coupling the digger unit to the lower stabilizer arm so that relative movement between the digger unit and the lower stabilizer arm is permitted in a direction transverse to the longitudinal axis of the lower stabilizer arm.

7. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point beneath and in vertical alignment with the pivot of the upper stabilizer arm and inward from and lower than the pivot of the lower stabilizer arm, a short linkage hinged respectively at its opposite ends to the outer end of the third arm and to the under side of the lower stabilizer arm between its midpoint and pivoted end, a hydraulic piston and cylinder assembly pivotally connected respectively at its two ends to the upper stabilizer arm between its midpoint and pivoted end and to the third arm between its midpoint and pivoted end, an endless digger unit disposed at the outer ends of the upper and lower stabilizer arms, means pivotally connecting the digger unit to the upper stabilizer arm, and means coupling the digger unit to the lower stabilizer arm so that relative movement between the digger unit and the lower stabilizer arm is permitted in a direction transverse to the longitudinal axis of the third arm.

8. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, an outwardly extending third arm pivotally supported at its inner end to the vehicle at a point lower than the pivot of the upper stabilizer arm and inward of the pivot of the lower stabilizer arm, the outer end of the third arm being coupled to the lower stabilizer arm at a point intermediate of its pivot end and midpoint, a hydraulic piston and cylinder assembly interposed and pivotally connected between the upper stabilizer arm and the third arm, and a digger unit disposed at the outer ends of the upper and lower stabilizer arms, said digger unit having a relatively large upper sprocket, a smaller lower sprocket, an endless bucket line carried at its respective two ends over the two sprockets, an endless conveyor extending through the upper sprocket transversely of the

sprocket and bucket line, means pivotally connecting the digger unit to the upper stabilizer arm, and means coupling the digger unit to the lower stabilizer arm so that relative movement between the digger unit and the lower stabilizer arm is permitted in a vertical direction.

9. In a trenching machine for attachment to a vehicle, the combination comprising an outwardly extending upper stabilizer arm pivotally supported at its inner end to the vehicle, an outwardly extending lower stabilizer arm pivotally supported at its inner end to the vehicle at a point lower than the pivot of the upper stabilizer arm, means pivotally connected to the upper stabilizer arm and to the lower stabilizer arm at locations spaced from their pivoted ends for applying a spreading force between the two arms, the linear distance between the pivoted inner end of the upper stabilizer arm and its connection with the spreading means being greater than the corresponding distance related to the lower stabilizer arm, an endless digger unit disposed at the outer ends of the upper and lower stabilizer arm, means pivotally connecting the digger unit to the upper stabilizer arm, and means slidably and pivotally coupling the digger unit to the lower stabilizer arm so that relative movement between the digger unit and the lower stabilizer arm is permitted in a vertical direction.

10. A trenching machine having a frame, an upper lever arm, a pivotal connection between one end of said upper lever arm and said frame, a bucket chain line frame, a pivotal connection between the other end of said upper lever arm and the upper end of said bucket chain line frame, a lower lever arm, a pivotal connection between one end of said lower lever arm and said frame, a sliding connection member, means for pivotally mounting said sliding connection member on the other end of said lower lever arm, a guide flange on said bucket chain line frame slidably engaged and supported in said sliding connection member, an extensible and retractable power

5 5

actuator, a pivotal connection between one end of said power actuator and an intermediate point on said lower lever arm, and a pivotal connection between the other end of said power actuator and an intermediate point on

10 said upper lever arm.

11. A trenching machine having a frame, an upper lever arm, a pivotal connection between one end of said upper lever arm and said frame, a bucket chain line frame, a pivotal connection between the other end of said upper lever arm and the upper end of said bucket chain line frame, a lower lever arm, a pivotal connection between one end of said lower lever arm and said frame, a sliding connection member, means for pivotally mounting said sliding connection member on the other end of said lower lever arm, a guide flange on said bucket chain line frame slidably engaged and supported in said sliding connection member, an extensible and retractable power actuator, a pivotal connection between one end of said power actuator and an intermediate point on the lower lever arm, and a pivotal connection between the other end of said power actuator and an intermediate point on the upper lever arm, the distance between the intermediate pivotal connection of the upper lever arm and the bucket chain line frame being less than the distance between the

15 20 25 intermediate pivotal connection of the lower lever arm and the bucket chain line frame.
